UNITED STATES PATENT OFFICE.

MAURICE E. CHASE, OF CAMBRIDGE, MASSACHUSETTS.

CONCRETE INSERT.

Application filed February 14, 1921. Serial No. 444,635.

To all whom it may concern:

Be it known that I, MAURICE E. CHASE, a citizen of the United States, and a resident of the city of Cambridge, in the county of 5 Middlesex and Commonwealth of Massachusetts, have invented certain new and useful Improvements in Concrete Inserts, of which the following is a full, clear, and exact specification.

10 In the erection of concrete edifices, it is customary to insert in the walls and ceilings certain attaching devices, which, after the cement has hardened, can be utilized for the suspension of piping and other elements.

15 Such devices are usually nailed upon the flooring or platform which is to be used for the temporary support of the concrete during its hardening, so that after the platforms are removed, the attaching devices 20 will remain embedded in the ceilings and ready for use. I have found them in practice to be uncertain, liable to become displaced and incapable of convenient attachment, and incapable of adjustment.

25 My invention has for its object the construction of a device of the kind which can be fastened upon the platform with a certainty of its remaining in place, which will support the piping without danger of detachment, which permits of a considerable 30 lateral variation in its connection with the pipes, from which the piping can be readily released whenever desired, which can be employed for the suspension of partitions, and 35 perform the other functions hereinafter set forth.

Fig. 1 is a sectional elevation showing one of my inserts fastened upon a platform. Fig. 2 is a sectional view of the insert with 40 the platform taken down, and embedded in the concrete, and showing it supporting a suspension device. Fig. 3 is a plan view of the device with its cover removed. Fig. 4 is a perspective view of another form of the 45 suspension device.

The concrete insert embodying my invention consists of a small metal box 1 shown in the drawings in approximately full size, with its bottom considerably narrower than 50 its top both in order to be readily cast, and to strongly retain itself in the concrete against any downward pull.

Through the bottom of the box 1 is a longitudinally disposed slot 2 adjacent the side 55 3, the closed portion 4 of the bottom being of considerable thickness and formed with

a rounded surface 5 at the side of the slot 2. Along the lateral edge of each side 3 and 6 at the top thereof, is an inclined flange 7, and slidably engaging these flanges is a 60 cover 9 having inwardly bent edges 10 fitting the flanges; the purpose of the cover being to close the box against the entrance of dirt and concrete. Slight depressions 11 near the ends, as shown in Fig. 5, retain the 65 cover in place.

Through the thickened bottom portion 4 are screw holes 12 through which screws 13 are inserted for fastening the box to the concrete-supporting platform 14, as illustrated 70 in Fig. 1. After the boxes 1 have thus been placed, and the covers 9 returned thereto, the concrete is poured upon the platform to the desired depth, and after it has suitably hardened, the platform planking 14 is re- 75 moved, the screws 13 tearing out therefrom, leaving the structure as illustrated in Fig. 2.

Then, or before the cover 9 has been replaced, a roller 15 is introduced within each box, each end resting upon a ledge 16 at the 80 end of the slot 2. When the lance-shaped head 17 of a suspension device 19 is inserted through the slot 2 sufficiently to permit the roller 15 to come between its neck 20 and the side 3 of the box, then the roller 15 be- 85 comes a clutch acting to prevent the withdrawal of the suspension device 19 no matter how hard the pull thereon. The suspension device can have a screw eye or hook 21 screwed into its lower end as indicated in 90 Fig. 2, or it can be formed with a hook 22 made integral therewith, as in Fig. 4.

The boxes being set in the ceiling with their slots 2 disposed transversely to the line of the boxes, the suspensions 19 can be 95 easily slid to one side or the other in order that the pipe supported thereby will be in perfect alinement.

If it is desired to remove the piping and the suspensions, all that needs to be done 100 is to press the latter upward, and then by pushing the roller 15 up and holding it, as by means of a finger, the suspensions can each be readily withdrawn from its box.

What I claim is:

1. A concrete insert comprising a box having an elongated slot through its bottom, a suspension device having a head adapted to be introduced through said slot and to be slid to different points thereof, and a loosely 110 disposed elongated roller reaching from end to end of said box and to be inserted into

the box through said slot, the box having means for holding the roller from dropping through said slot when the roller is parallel therewith, said roller acting to lock said suspension device within said box by engagement with its head.

2. A concrete insert comprising an elongated box having a longitudinally disposed slot through its bottom, a suspension device having a lance-shaped head and contracted neck, an elongated roller loose in said box, and means for preventing said roller from dropping from said box when in a horizontal position, whereby to engage said head and retain the suspension device at different points in said box.

3. A concrete insert comprising a box narrower at its bottom than at its top and having a longitudinally disposed slot through its bottom near one side thereof, the portion

of the bottom at the other side of said slot being thickened and provided with screw holes, the surface of said thickened portion adjacent the slot being rounded, a suspension device having a head easily introduced through said slot, and a roller adapted to come between said head and a side of the slot.

4. A concrete insert comprising an elongated box having a widened top and a longitudinally disposed slot through its bottom, the slot having a ledge at each end, a roller terminally resting upon said ledges, and a suspension device having a head adapted to be introduced through said slot and to be locked therein by said roller.

In testimony that I claim the foregoing invention, I have hereunto set my hand this 12th day of February, 1921.

MAURICE E. CHASE.
